(57) **CLAIM**

What is claimed is the ornamental design for a stool, as shown and described.

DESCRIPTION

FIG. 1 is a front and right perspective view of a stool showing my new design.

FIG. 2 is a right side elevation view thereof; and, FIG. 3 is a front elevation thereof, with the rear elevation being a mirror image of the front.

The broken lines in the drawings depict portions of the stool that form no part of the claimed design.
